UNITED STATES PATENT OFFICE.

MARTIN MEYER, OF OMAHA, NEBRASKA.

PORTABLE TOILET-SEAT.

1,223,065.

Specification of Letters Patent.

Patented Apr. 17, 1917.

Application filed January 6, 1915. Serial No. 805.

To all whom it may concern:

Be it known that I, MARTIN MEYER, a citizen of the United States, residing at Omaha, in the county of Douglas and State of Nebraska, have invented certain new and useful Improvements in Portable Toilet-Seats, of which the following is a specification.

This invention relates to an improvement in portable toilet seats, and has for its object 10 to provide a toilet seat which may be folded or collapsed for convenient transportation. A secondary object relates to certain details of construction conducing to utility and durability.

15 The invention consists of the novel construction, combination and arrangement of parts as described herein and claimed, and as illustrated in the accompanying drawing, wherein,—

20 Figure 1 is a side view of the device, the legs being folded, the lid being shown broken away and elevated. Fig. 2 is a sectional view, as on line 2 2 of Fig. 3. Fig. 3 is a plan view of the device, the legs being 25 folded and the lid being broken away. Fig. 4 is a bottom plan view of the seat. Fig. 5 is a view of the device in side elevation. Fig. 6 is a detail view showing a bracket used for 30 mounting the legs on the seat. Fig. 7 is a perspective view showing a box or frame for the mounting of a paper roll.

Referring now to the drawing, numeral 1 indicates a toilet seat preferably of rectangular form having an aperture α and provided 35 on its bottom to open on its front and back with a pair of U-shaped grooves, the rectilinear parts a of said grooves, midway between their ends, being formed parallel with reference to each other, in, near and parallel 40 with the front and back of the seat, the remaining parts b of each U-shaped groove being formed divergent from the part a .

At 2, best shown in Fig. 4, are indicated 45 U-shaped supporting members, to provide legs, said members being arranged in pairs, the rectilinear base c of each pair being seated in a groove a , and when folded or collapsed, the divergent parts or legs 3 are seated in grooves b in the plane of the seat 50 so that they will not be obtrusive. At 4 are indicated staples, holders or brackets preferably countersunk in the bottom of the seat

for pivotally supporting the bases c in grooves a , said holders being provided with guards or stops 5 extending laterally therefrom for engagement with the legs, and thereby supporting them, relatively, in inclined or divergent positions when extended. At 6 are indicated keepers or buttons which may be countersunk in the bottom of the seat 60 and may be partly rotated for engaging and holding the legs in the grooves b when the parts are collapsed; and preferably threaded on each leg at its free end, is a foot-piece 7 so that the legs will not sink into the ground 65 when in use.

At 8 is indicated a recess formed to open on the top of the seat, near one of its sides; and as best shown in Fig. 7, a small roll of 70 toilet paper may be carried by a box frame 9, said frame being mounted in said recess.

At 10 is indicated a lid, the hinges for mounting it on the seat being indicated at 11. Each hinge member on the seat, outwardly of the lid, is provided with an upwardly projecting stop or lug 12, the hinge members for the lid also being provided with the projections 13 adapted to engage the lugs 12, for suitably supporting the lid inclinedly when it has been swung upwardly. 80 A suitable handle for carrying the device is indicated at 14.

As thus described the device provides a convenient toilet stool which may be collapsed to occupy a very limited space when 85 transported, these being the principal objects desired, since it is for the use of automobile excursionists, or for use in the fields or in camp.

Having fully described the several parts 90 a further explanation relating to their function is not necessary. It is understood that there is no limitation as to size, proportion or material to be employed, and that minor details of construction may be changed, the 95 scope of the invention being determined by the appended claim.

What I claim and desire to secure by Letters Patent is,—

A portable toilet device, including an 100 apertured seat having oppositely arranged approximately U-shaped grooves in its underside, correspondingly shaped supporting members having bearings in said approxi-

mately U-shaped grooves, said supporting members having divergent leg-forming portions, and holders secured to said seat and adapted to provide for pivotally connecting 5 said supporting members to said seat, said holders having guards extending laterally therefrom to engage the divergent leg-forming portions of said supports and limit their

movement as the latter are disposed in vertical position.

In testimony whereof, I have affixed my signature in presence of two witnesses.

MARTIN MEYER.
